Application December 13, 1933, Serial No. 702,211

42 Claims. (Cl. 153—54)

5 My invention relates to an improved method and apparatus for manufacturing metal sheets and strips, and particularly to an improved method and apparatus for straightening or leveling relatively wide thin material or for breaking or loosening scale on such material by a series of bending operations.

10 The subject matter of the present application is closely related to and is an improvement upon that of my copending application Serial No. 663,519 filed March 30, 1933, of which the present application is a continuation-in-part.

15 In the operation of straightening sheet metal as by leveler machines it has been customary to provide a series of upper and lower working rolls for imparting a series of bends to sheet metal, there being a comparatively large number of rolls in each of the series. Substantially the only adjustment for the rolls is a vertical one, 20 and in general it has not been customary to provide these working rolls with backing rolls.

25 Roller levelers of the type described above have been somewhat unsatisfactory for the reason that they have not been suitable for straightening metal of various thicknesses and such machines are not sufficiently flexible in their operation to adapt them for sheet metal of a fairly wide range of thicknesses. When 30 backing rolls have been employed, it has usually been necessary to pass the metal between all of the rolls regardless of the condition of the metal and the degree of straightening that has been required.

35 Whenever working rolls are used in combination with backing rolls, the ideal arrangement is that in which all of the cooperating rolls are in alignment as in the usual 4-high mill. In such case all of the forces of compression between the several rolls are in alignment with the plane of their axes and there are no lateral components. If the rolls are in vertical alignment, there are no horizontal components of 40 these forces.

45 However, when a backing roll for each working roll is used in roller levelers it will be appreciated that, if the backing rolls are of sufficiently large diameter, the distances between adjacent pairs of working rolls would be too great to impart the abrupt small bends that are necessary to properly straighten the material being rolled.

50 If backing rolls of the usual type and size are provided for each pair of working rolls, the latter may be placed sufficiently close together but 55 the arrangement has certain serious disadvan-

tages. The horizontal components of the rolling forces are so great that objectionable flexure of the working rolls is produced since the latter are unsupported in this direction.

5 The provision of spacing rolls between adjacent pairs of working rolls would reduce deflection of the latter because of horizontal components of rolling forces, but the size of the backing rolls is limited, and in order to provide the necessary rigidity of the rolling structure it would be necessary to increase the diameter of the working rolls beyond that suitable for use in a roller leveler. The diameter of the working rolls must be maintained relatively small, as will be appreciated, in order to secure 10 relatively sharp bending of the sheet material.

15 In accordance with the present invention, I provide an arrangement by means of which the foregoing disadvantages are avoided. The improved arrangement permits the employment of 20 small working rolls and relatively large backing rolls, thus providing sufficient rigidity for very wide material and reducing the deflection of the working rolls when under rolling pressure. The working rolls may operate on close centers for 25 leveling the material and also for breaking or loosening scale on sheet or strip material.

25 The ratio of the diameter of the backing rolls to that of the working rolls may vary through 30 a range of, for example, from 3:1 to 6:1. A ratio of approximately 4:1 has been found to be 35 very satisfactory in actual service. Such ratios are not possible with roller levelers of ordinary or usual design, because if the working rolls were sufficiently small to perform the work for 40 which applicant's working rolls are designed, space would not permit the use of backing rolls of such diameter as to fall within these ratios. The working rolls would, in such case, be insufficiently supported.

45 The large diameter of the backing rolls reduces the angle between the horizontal and the common tangent of the engaging surfaces of the backing rolls and the working rolls in their offset positions, and accordingly materially reduces the horizontal components of the rolling forces. Also, any given horizontal deflection of the working rolls has a smaller vertical component since, as the diameter of the backing 50 rolls increases, any deflection of the working rolls is more nearly entirely horizontal.

55 The roller leveler of the present invention consists of a plurality of main units of small working rolls and large backing rolls which may be operated in substantially any desired

relation to impart the desired degree of bending and the number of bending operations that are desirable in straightening sheet metal of any given thickness. In addition, the leveler 5 prises a unit having a series of larger working rolls for preventing bowing or curving of the ends of the metal strip that are not under tension when passing through the leveler. The working rolls of the several units are independently driven whereby, for example, one, two, or three units may be in operation at the same time upon any given material.

The working rolls of the main units are arranged in pairs in each unit, and each pair is 15 provided with a relatively large backing roll in order to insure that the working rolls will be sufficiently rigid for rolling relatively thick material and yet be small enough and placed sufficiently close together to act effectively to produce abrupt reverse bends in thin material. The pairs of working rolls in each unit are staggered relatively to each other as are the upper and lower backing rolls for cooperating therewith.

20 23 The backing rolls are relatively adjustable vertically in accordance with the gauge or thickness of the metal to be rolled. The working rolls are adjustable horizontally, whereby they may assume various positions around the 30 circumferences of their respective backing rolls. This adjustment changes the angles between the planes of the axes of the respective pairs of working rolls and varies the relative degrees of bending of sheet metal upon entering and leaving the working rolls of each unit.

35 The details of the roller leveler of my invention will be described in connection with the accompanying drawings, in which Fig. 1 is a view in side elevation of a roller leveler constructed in accordance with my invention; Fig. 40 40 is a longitudinal vertical section of the machine of Fig. 1 taken on line II—II of Fig. 4; Fig. 3 is a view partly in end elevation and partly in transverse section taken on line III—III 45 of Fig. 1; Fig. 4 is a view in horizontal section taken partially on line IV—IV and partially on line A—B of Fig. 1, the driving mechanism for the working rolls for the several units of the roller leveler machine being shown diagrammatically; Figs. 5, 6 and 7 are diagrammatic views of the working rolls and backing rolls of a main unit in various relative positions and illustrating the corresponding degrees of bending of metal passing therethrough; and Figs. 8 50 55 and 9 are diagrammatic views of all of the working rolls of the roller leveler with a strip of metal passing therethrough.

60 Referring to the drawings, a roller leveler machine constructed in accordance with my invention comprises a housing 1 consisting of two side frames 2 and 3 that are suitably spaced and connected together by means of transverse beams 4 at the top thereof and by beams 5 at the bottom.

65 Each of the side frames 2 and 3 is provided at its upper portion with two downwardly projecting members 6 which separate the space between the end portions of the frames into a series of three compartments. The lower portion of each 70 75 of the frames 2 and 3 is similarly provided with two upwardly projecting members 7 for dividing the lower portion of the frame into a series of three compartments that are slightly offset with respect to the compartments in the upper portion of the frame. This arrangement is shown

and described by way of example as the compartments may be, if desired, in vertical alignment by suitably proportioning the chucks for the bearings of the rolls.

An upper and a lower compartment that are in approximately vertical alignment constitute, in effect, a housing or larger compartment for an operating unit of the roller leveler machine. The operating units 8 and 9 are similar in all substantial respects and one of them will be described in detail by way of example. Operating unit 10 is of different type.

10 15 The unit 8 comprises upper and lower pairs of relatively small working rolls 12 that are disposed in staggered relation. Each pair of working rolls 12 is provided with a single backing roll 13 of relatively large diameter, the backing rolls being offset horizontally, that is, out of vertical alignment by a distance that is substantially identical with the distance by which the corresponding working rolls are offset or out of vertical alignment.

20 25 The lower backing roll 13 is supported at its ends in suitable anti-friction bearings 14. Each of the bearings 14 is mounted in a bearing chuck 15 that, by way of example, is of such dimensions as to occupy the width of the corresponding compartment in the frame, and is secured in position by, for example, having on each side thereof a tongue-and-groove connection to the adjacent portions of the frame.

30 35 The working rolls 12 of the lower pair are mounted in bearings 16 that are carried at each end of the rolls by a bearing chuck 17. A vertical eye-bolt 18 and a spring 19 at the outer end thereof provides a yielding connection between the chucks 15 and 17 whereby relative movements of these chucks may occur in order to provide adjustment of the positions of the working rolls 12 of the lower pair circumferentially of the lower backing roll 13.

40 45 The upper backing roll 13 is mounted in bearings 14 similar to those previously described in connection with the lower backing roll, and the bearing chucks 21 therefor are each yieldingly secured to the upper portion of the side frames 2 and 3 by means of four eye-bolts 22 and relatively heavy coil springs 23 for permitting vertical movement of the chuck 21 relative to the housing for adjusting the distance between the backing rolls 13 and thereby correspondingly adjusting the distances between the upper and the lower pairs of working rolls 12.

50 55 A chuck 24 supports the bearings 16 of the upper working rolls 12. Two eye-bolts 25 and springs 26 yieldingly connect the chuck 24 to the chuck 21 whereby the chuck 24 may be adjusted horizontally for adjusting the positions of the upper working rolls 12 circumferentially of their backing roll 13. The springs 26 maintain the working rolls 12 in engagement with the backing roll 13.

60 65 A screw-down mechanism for adjusting the vertical positions of the bearing chucks 21 for the upper backing roll 13 comprises a hand-wheel 28 mounted on a horizontal shaft 29 having pinions 30 thereon for rotating beveled gears 31 on the upper ends of screw-threaded rods 32 which extend through the upper portion of the frames and engage the tops of the bearing chucks 21. Rotation of the screw-threaded shafts 32 in one direction forces the bearing chucks 21 downwardly against the force of the springs 23 while adjustment of the screw-threaded shafts 32 in the opposite direction per-

mits the springs 23 to draw the bearing chucks 21 upwardly with corresponding effects upon the distances between the backing rolls 13 and the pairs of working rolls 12. These adjustments 5 are necessary in order to provide for rolling sheet metal of different gauges or thicknesses.

The adjustment of the horizontal positions of the pairs of bearing chucks 17 and 24 for the lower and the upper pairs of working rolls respectively are controlled by a mechanism comprising a hand-wheel 34, a horizontal shaft 35, worm gear mechanisms 36, screw-threaded shafts 37 and links 38 actuated thereby and connected to the respective chucks. Rotation 15 of the hand-wheel 34 in one direction causes the chucks 17 and 24 to be actuated to the left as viewed in Figs. 1, 2 and 4, to cause the respective pairs of working rolls to correspondingly adjust their angular positions with respect to 20 their respective backing rolls. This adjustment also affects the plane of alignment of the axes of each pair of working rolls and the angle between these planes. Rotation of the hand-wheel 34 in the opposite direction effects corresponding 25 adjustments in the opposite direction.

The construction and arrangement of the operating unit 9 is similar in all essential respects to those described for the unit 8, the horizontal adjustments of the bearing chucks 17 30 and 24 for the units 9 being made simultaneously with those for the unit 8 by means of links 39 and 40 which connect the corresponding bearing chucks 17 and 24 of the units 8 and 9. This arrangement is shown by way of example 35 only, as I may, if desired, provide separate means for horizontal adjustment of the units 8 and 9. Equivalent relative movements of the rolls may also be obtained by moving the backing rolls horizontally instead of the working rolls.

40 The leveler unit 10 comprises an upper and a lower series of rolls 42 that are larger than the working rolls 12 of the units 8 and 9 and that, as illustrated, are unsupported by backing rolls. The latter are omitted because the rolls of unit 10 do not perform the heavy duty required 45 of the working rolls 12, but it is understood that backing rolls may be employed, if desired. There are four rolls 42 in the upper series that are carried by vertically movable frames or chucks 50 43 controlled by a screw-down mechanism identical with that for units 8 and 9. The lower series of three rolls 42, staggered with respect to those of the upper series, is carried by chucks 44 pivotally supported at 45. The position of 55 the other ends of the chucks 44 is adjusted by means of wedges 46, Figs. 1, 2, 3 and 4, controlled by a hand-wheel 47 having a screw-threaded shaft 48 with a traveling nut 49 thereon connected to the wedges. The latter are 60 connected by a bar 50.

Referring particularly to Figs. 2 and 4, suitable guides for sheet metal traversing the roller leveler machine comprise horizontal supporting frames 52 of metal plates or wide bars 53 at 65 the outer ends of the machine and horizontal intermediate frames 54 of similar material between the several units. The frames 52 and 54 are of suitable form for guiding and supporting the metal while it is passing through the machine. At each end of the machine and inclined 70 upwardly at an angle to the guide frames 52 is a frame 55 for guiding the material into the rolls or for permitting variations in the angle of the material in leaving the machine.

75 Reference may now be had to Fig. 4 in which

are illustrated certain details of the driving mechanism for the respective pairs of working rolls of the several units 8, 9 and 10. Each of the units 8 and 9 is independently driven by a similar mechanism comprising a motor 51, a gear mechanism 58 and shafts 59 having suitable universal couplings 60 and 61, respectively, connected to the gear mechanisms 58 and rolls 12. Since each unit is provided with its individual driving motor 51, the relative speeds of the 10 working rolls of the several units may be adjusted as desired by suitably controlling the speed of the respective motors 51.

As also shown in Fig. 4, the rolls 42 of unit 10 are driven by a motor 51, a gear mechanism 15 58 and shafts 59 having universal couplings 60 and 61, respectively, connected to the gear mechanism 58 and to certain of the rolls 42. Shafts 59 are connected to the two inner rolls 42 of the upper series, and, as shown in Fig. 1, each of 20 these rolls is geared to the adjacent outer roll by means of gears 62 and an idler gear 63. In the lower series of rolls, the two on the right, Fig. 1, are directly driven and the one on the left being geared to the adjacent roll by gears 25 62 and an idler gear 63. Accordingly, all of the rolls 42 operate at the same speed and in the same direction.

In the operation of the roller leveler machine it may be assumed that sheet metal is to be 30 rolled thereby and that all of the units 8, 9 and 10 are to be in operation to successively roll the metal. The screw-down mechanisms comprising the hand-wheels 28 will be adjusted to suitably space the backing rolls and the working rolls of the several units. The hand-wheel 34 will be adjusted to correspondingly adjust the 35 positions of the working rolls of the units 8 and 9 with respect to each other and with respect to their respective backing rolls. The 40 latter adjustment of the working rolls governs the degree of bending to which the metal is subjected upon entering the working rolls and the degree of bending that is applied thereto when the metal leaves the unit 8 in the direction of the unit 9 and leaves the latter unit in the direction of the unit 10, it being understood 45 that tension is exerted upon the metal between the several units.

When the working rolls 12 are adjusted 50 around the circumferences of the relatively large backing rolls 13, they will be moved toward or away from positions of alignment with the backing rolls in which the horizontal or lateral components of the rolling forces are substantially 55 zero. The more nearly a working roll approaches such position of alignment, the greater is the portion of the rolling load that is assumed by it. It is therefore highly advantageous that adjustments of the working rolls to exert 60 greater force upon the material also reduces the components which tend to deflect or bend the working rolls.

While the working rolls of the units 8 and 9 may, if desired, be adjusted to similar or corresponding positions, whereby the amount of work performed by them is substantially equal, it may be preferable to adjust the working rolls of the unit 8 to perform a greater amount of work than is imposed upon the working rolls of 70 the unit 9. Better results are obtained when the degree of bending is progressively diminished as the metal passes through the machine.

The metal passes through the several units 75 successively and the bending that is exerted by

the staggered sets of working rolls operates to impart a straight flat surface to the sheet metal. By reason of the adjusting mechanisms, the distribution of work between the several units 5 may be varied as desired and suitable adjustments may be made in order that the working rolls may exert suitable bending effects to accomplish the desired results.

Due to the abrupt small bends imparted to 10 the strip by the working rolls 12, it is possible for the leading end of the metal to curl down and the trailing end to curl up as they leave such rolls. To prevent this possibility, the larger rolls 42 are provided and by means of the 15 screw-down mechanism therefor and the wedges 46 they can be so adjusted as to deliver the entire strip or sheet in a perfectly flat and leveled condition.

Referring to Figs. 5, 6 and 7, various relative 20 positions of the rolls of an operating unit such as 8 or 9 are diagrammatically shown therein. These views also show the degrees of bending of the sheet metal as it leaves or enters the 25 working rolls in the several positions of the latter with respect to their respective backing rolls.

In Fig. 5, the working rolls are adjusted for 30 substantially equal load upon the members of each pair since their respective lines of centers with the backing rolls are at substantially equal angles with the vertical. However, the material leaves the working rolls at an undesirable angle to the horizontal since it may rub with considerable 35 force on the stationary guides and scratching of the metal may result.

In Fig. 6, both pairs of working rolls have 40 been adjusted to the left as viewed in the drawings, and the result is to cause the right-hand working roll of each pair to assume a greater portion of the rolling load since their lines of centers make smaller angles with the vertical. The angle of the metal with the horizontal on leaving the working rolls is smaller than that in Fig. 5, because the greater degree of bending 45 now occurs upon entering the rolls.

When the working rolls have been adjusted to the relative positions shown in Fig. 7, the right-hand rolls have assumed a still greater portion of the rolling load and a still greater 50 degree of bending occurs when entering the rolls while that upon leaving the rolls has been diminished to such extent that the metal leaves the rolls substantially in the plane of the pass line through the machine.

As the working rolls are moved to the right 55 through successive positions of which Figs. 5, 6, and 7 are representative, the right-hand working rolls assume a progressively heavier portion of the rolling load, at the same time the horizontal component of the rolling force becomes less as the forces transmitted to the working rolls by the backing rolls and the metal being rolled are more nearly in alignment.

As a result, the greater the load upon any 65 given working roll, the smaller is the horizontal component of the rolling force and tendency to cause flexure of the working roll is diminished. The opposite effects are of course produced upon the working rolls moved into positions away 70 from alignment of the rolling forces, but the increase in the horizontal component of the rolling force carried thereby is offset by the reduction in the rolling force.

While the adjustments of the relative positions of the pairs of working rolls and their 75

backing rolls have been shown and described as effected by moving the working rolls around the axes of the backing rolls, it will be understood that substantially similar results may be secured by moving at least one of the backing rolls horizontally to change the horizontal distance therebetween.

The path of metal through the roller leveler machine is shown diagrammatically in Figs. 8 and 9. It will be noted that in each unit, the 10 bending of the metal as it enters the rolls is greater than upon leaving whereby the metal is approximately straight between units. The latter effect is also insured in part by the control of the driving motors to exert tension upon 15 the metal between units. In Fig. 8, both of the units 8 and 9 are adjusted for greater degrees of bending than they are in Fig. 9. In the latter view, the unit 10 is adjusted for greater initial bending than in Fig. 8.

It may be unnecessary to pass metal through all of the three units of the roller leveler machine, and by means of the construction and arrangement described above I may provide that sheet metal passes, for example, through the 25 unit 8 only, the working rolls of the units 9 and 10 being adjusted to permit the free passage of metal therethrough. The latter units will not be driven under these circumstances and there will be, of course, a corresponding saving 30 in power.

In case it is desirable to operate two units for rolling sheet metal, for example, the unit 8 may be idle with its working rolls 12 separated to permit the metal to pass freely therethrough. 35 The units 9 and 10 are adjusted for operation for producing the desired results, and the operation is as otherwise described for the operation of the entire machine.

As best shown in Figs. 1, 2 and 3, each of the 40 side frames 2 and 3 consists of an upper portion 65 and a lower portion 66 that are connected at their respective adjacent ends by means of a projecting tongue 67 which extends into a slot 68 and a wedge 69 which locks these parts 45 together. This arrangement permits the removal of the entire upper half of the machine upon removal of all of the wedges 69.

The upper backing rolls 13 and upper working rolls 12 and the upper series of rolls 42 remain in position in the upper half of the housing by reason of the connection of their bearing chucks to the frames and to each other. The roll assembly for the upper half of each unit 50 may be removed by disconnecting the eye-bolts 55 22, each bearing chuck 21 being provided with a projection or trunnion 70 for engagement by suitable hoisting mechanism. The chucks 15 for the lower backing rolls 13 are also provided with trunnions 70 for similar purposes. 60

The sectional construction of the housing and the connection of the rolls and their bearing supports to the corresponding parts of the main housing provide a simple and convenient arrangement for assembling and disassembling the entire machine or the repair or replacement of any of its working parts.

From the foregoing it will be noted that I have provided a roller leveler machine comprising a series of aligned units for successively rolling sheet metal. The operation of the machine is extremely flexible since one, two or three units may be employed in accordance with the character of the material that is to be rolled 75

or the treatment that is necessary for straightening it.

Further flexibility of operation is obtained by the provision of separate means for adjusting the relative positions of the backing rolls of the several units and the provision of means for adjusting the working rolls of one of the units independently of the other units. Suitable operating conditions may be maintained by adjusting the controllers of the several driving motors to exert tension upon the sheet metal between the several units.

The arrangement whereby the backing rolls may be adjusted vertically provides suitable means for adapting the machine to the gauge of the material to be rolled, while the adjustment of the working rolls determines the degree of bending that is exerted by each unit and in addition determines the relative degrees of bending of metal upon entering and leaving the working rolls of each unit. By means of this latter arrangement the machine may be conveniently adjusted for exerting a relatively large degree of bending when the metal enters the machine and a relatively small degree of bending when the metal leaves the machine in order that the metal may leave the machine at an angle to the horizontal that varies therefrom as little as possible.

0 The provision of the different types of units, one type such as units 8 and 9 with small working rolls adapted for heavy duty in reversely bending sheet metal, and the other type for smoothing out curved portions for preventing bowed end portions permits the leveling of metal strip to render it flat throughout its entire length, including parts delivered without tension. The combination of these units secures results that can not be secured by levelers having a single type of rolls.

The abrupt reverse bends produced by the small working rolls of the main units effectively loosen or break the scale on strip or sheet material as it is passed through them, and hence renders the machine, or one or more units thereof, particularly suitable for scale breaking purposes.

The foregoing and other advantages will be apparent to those skilled in the art of construction and operation of roller leveler machines.

I claim:

1. A roller leveler machine comprising a pair of upper working rolls, a pair of lower working rolls in staggered relation thereto, a backing roll for each pair of working rolls, the centers of said backing rolls being out of vertical alignment, and means for adjusting each pair of working rolls around the corresponding backing roll.

0 2. A roller leveler machine comprising a pair of upper working rolls, a pair of lower working rolls, a backing roll for each pair of working rolls, and horizontally movable means for adjusting said working rolls circumferentially of the backing rolls therefor.

0 3. A roller leveler machine comprising a pair of upper working rolls, a pair of lower working rolls in staggered relation thereto, a backing roll for each pair of working rolls, the axes of said backing rolls being out of vertical alignment, and means for varying the alignment of the respective pairs of working rolls and thereby varying the relative degree of bending of material upon entering and upon leaving the working rolls.

5 4. A roller leveler machine comprising a pair

of upper working rolls, a pair of lower working rolls in staggered relation thereto, a backing roll for each pair of working rolls, the axes of said backing rolls being out of vertical alignment, and means for varying the angle of sheet metal with respect to the horizontal upon entering and upon leaving said working rolls, said means comprising devices for simultaneously adjusting the pairs of working rolls circumferentially of their respective backing rolls.

5

5 10 5. A roller leveler machine comprising a pair of upper working rolls, a pair of lower working rolls, a backing roll for each pair of working rolls, means for adjusting the relative positions of said backing rolls vertically, and horizontally 15 movable means for adjusting the positions of said working rolls relative to their respective backing rolls.

5 15 20 6. A roller leveler machine comprising a housing, an upper and a lower pair of working rolls, a backing roll for each pair of working rolls, a vertically adjustable bearing support for each of the ends of the upper backing roll, and a horizontally adjustable bearing support for the ends of each pair of working rolls.

5 25 25 7. A roller leveler machine comprising a housing, an upper and a lower pair of working rolls, a backing roll for each pair of working rolls, a vertically adjustable bearing support for each of the ends of the upper backing roll, a horizontally adjustable bearing support for the ends of each pair of working rolls, and means for connecting each bearing support for a pair of working rolls to an adjacent bearing support 30 for the backing roll cooperating with said pair 35 of working rolls.

5 30 40 8. A roller leveler machine comprising a housing, an upper and a lower pair of working rolls, a backing roll for each pair of working rolls, a vertically adjustable bearing support for each of the ends of the upper backing roll, a horizontally adjustable bearing support for the ends of each pair of working rolls, means for yieldingly connecting the bearing support for the upper backing roll to said housing to yieldingly hold said supports and said backing roll to their uppermost positions, and means for yieldingly connecting each bearing support for a pair of working rolls to a bearing support for the corresponding backing roll for permitting 50 relative movement therebetween.

5 45 55 9. A roller leveler machine comprising a housing, an upper and a lower pair of working rolls, a backing roll for each pair of working rolls, a vertically adjustable bearing support for each of the ends of the upper backing roll, a horizontally adjustable bearing support for the ends of each pair of working rolls, means comprising springs for connecting the bearing supports for the upper backing roll to said housing 60 to yieldingly hold these supports and said upper backing roll to their uppermost positions, a screw-down mechanism for adjusting the vertical positions of the upper backing roll bearing supports against the force of said springs, means 65 comprising springs for connecting each of the bearing supports for the ends of each pair of working rolls to a bearing support for the corresponding backing roll for yieldingly retaining them in engagement but permitting relative 70 movement therebetween, and means for moving the working roll bearing supports horizontally.

5 70 75 10. A roller leveler machine comprising a plurality of aligned operating units for successive-

- ly rolling sheet metal passing therethrough, each of said units comprising two pairs of cooperating working rolls, means common to the rolls of each pair of said working rolls comprising the sole means for preventing them from being deflected between their ends by the rolling forces encountered, and means for independently adjusting the working rolls of one of said units with respect to those of another unit in the series for varying the relative effects of said units upon said sheet metal.
11. A roller leveler machine comprising a plurality of aligned operating units for successively rolling sheet metal passing therethrough, each of said units comprising two pairs of cooperating working rolls, means common to the rolls of each pair of said working rolls comprising the sole means for preventing them from being deflected between their ends by the rolling forces encountered, and means for independently adjusting the working rolls of each of two of said units of the series for varying their relative effects upon said sheet metal.
12. A roller leveler machine comprising a plurality of aligned operating units for successively rolling sheet metal passing therethrough, each of said units comprising two pairs of cooperating working rolls and a backing roll for each pair of working rolls, and means for independently adjusting the backing rolls of one of two adjacent units for varying the relative effects of said adjacent units upon said sheet metal.
13. A roller leveler machine comprising a plurality of operating units, each unit comprising a plurality of working rolls and backing rolls therefor, means for independently driving the working rolls of the several units, whereby one or more units may be operated at any given time, and means for separately adjusting the relative positions of the backing rolls of the several units.
14. A roller leveler machine comprising a plurality of operating units, each unit comprising a plurality of working rolls arranged in staggered relation, and means for independently driving the working rolls of the several units to tend to operate the working rolls of the second and third units progressively faster than those of the first unit to thereby exert tension upon sheet metal traversing said machine.
15. A roller leveler machine comprising a plurality of operating units, each unit comprising a plurality of working rolls arranged in staggered relation, and means for driving the working rolls of the several units simultaneously but independently of each other to exert tension between said units on sheet metal traversing said machine.
16. A roller leveler machine comprising a series of aligned operating units for successively rolling sheet metal passing therethrough, each of said units comprising a plurality of upper and lower working rolls arranged in staggered relation, separate driving means for the working rolls of the respective units, and means for adjusting the working rolls of one of said units independently of the other units to vary the effect of said one unit upon said sheet metal.
17. A roller leveler machine comprising a series of aligned operating units for successively rolling sheet metal passing therethrough, each of said units comprising a plurality of upper and lower working rolls arranged in staggered relation, separate driving means for the working rolls of the respective units, and means for adjusting the working rolls of one of two adjacent units to vary the relative effects of said adjacent units upon said sheet metal.
18. A roller leveler machine comprising three operating units each including a plurality of working rolls and backing rolls therefor, means for adjusting the positions of certain of the backing rolls, means for adjusting the relative positions of the working rolls of one of said units independently of the other units, and means for adjusting the relative positions of the working rolls of the remaining two units simultaneously.
19. A roller leveler machine comprising a housing having a series of compartments therein, a series of aligned operating units mounted in the respective compartments, each of said units comprising a series of working rolls, backing rolls therefor, means connected to said housing for adjusting the relative positions of the backing rolls of each unit, and means connected to said housing for adjusting the relative positions of said working rolls of each unit.
20. A roller leveler machine comprising a housing having a series of compartments therein, a series of aligned operating units mounted in the respective compartments, each of said units comprising a series of working rolls, backing rolls therefor, means connected to said housing for adjusting the relative positions of the backing rolls of each unit, and means connected to said housing for adjusting the positions of the working rolls of each unit relative to their respective backing rolls.
21. A roller leveler machine comprising a housing having a series of compartments therein, a series of aligned operating units mounted in the respective compartments, each of said units comprising a series of working rolls, backing rolls therefor, means connected to said housing for independently adjusting the relative positions of the backing rolls of the several units, and means connected to said housing for adjusting the positions of the working rolls of certain of said units with respect to the working rolls of another unit.
22. A roller leveler machine comprising two pairs of cooperating working rolls, a backing roll for each pair of working rolls, and means for adjusting the relative positions of a pair of working rolls and their backing rolls to vary the degree of bending of sheet metal upon entering and leaving said working rolls, such adjustment reducing the horizontal component of the rolling force on any working roll as the rolling force thereon is increased.
23. Apparatus for reversely bending sheet metal comprising two pairs of cooperating working rolls, a backing roll for each pair of working rolls, and means for adjusting the relative positions of a pair of working rolls and their backing roll to vary the degree of bending of sheet metal upon entering and leaving said working rolls, such adjustment causing the horizontal component of the rolling force on each working roll to vary inversely with the rolling force thereon.
24. Apparatus for reversely bending sheet metal comprising an upper and a lower pair of cooperating working rolls, a backing roll for each pair of working rolls, and means for adjusting each pair of working rolls around the axis of the adjacent backing roll, such adjustment reducing the horizontal component of the rolling pressure tending to produce flexure of

- any working roll as the rolling pressure thereon is increased by the adjustment.
25. Apparatus for reversely bending sheet metal comprising two pairs of cooperating working rolls, a backing roll for each pair of working rolls, and means for adjusting each pair of working rolls around the axis of the adjacent backing roll, such adjustment causing the horizontal component of the rolling pressure on each working roll to increase or decrease according as the rolling pressure on such working roll is decreased or increased, respectively.
26. A roller leveler machine comprising a series of operating units each of which comprises two pairs of cooperating working rolls, a backing roll for each pair of working rolls, and means for varying the relative angular positions of said working rolls and their corresponding backing rolls while maintaining engagement therebetween.
27. Apparatus for reversely bending sheet metal comprising a plurality of operating units each of which comprises two pairs of cooperating working rolls, a backing roll for each pair of working rolls, and means for varying the relative horizontal and vertical positions of each of said backing rolls and its corresponding pair of working rolls.
28. Apparatus for reversely bending sheet metal comprising a pair of upper working rolls, a pair of lower working rolls, a backing roll for each pair of working rolls comprising the sole means for preventing said rolls from being deflected and means for circumferentially adjusting said working rolls about the backing roll.
29. Apparatus for reversely bending sheet metal comprising a plurality of rolls for engaging metal passing therebetween, the rolls for engaging one side of said metal comprising a pair of working rolls of relatively small diameter and a backing roll therefor comprising the sole means for preventing deflection of the working rolls, said backing roll being sufficiently larger than the working rolls and the working rolls mounted sufficiently close together against the backing roll to prevent objectionable deflection of the working rolls by the rolling forces encountered.
30. Apparatus for reversely bending sheet metal comprising upper and lower pairs of cooperating working rolls of relatively small diameter arranged in staggered relation, and a backing roll for each pair of working rolls, said backing roll comprising the sole means for preventing deflection of the associated working rolls and being sufficiently larger than the working rolls and the working rolls mounted sufficiently close together thereagainst to prevent objectionable deflection of the working rolls by the rolling forces encountered.
31. A roller leveler machine comprising a series of conjointly operative units for successively leveling sheet metal, certain of said units comprising relatively small working rolls for producing abrupt bends in said metal strip, relatively large backing rolls for said working rolls, and the last of said units in the series comprising two series of working rolls of larger diameter than those in the preceding units in the series for producing relatively slight bends in the metal strip.
32. Apparatus for reversely bending sheet metal comprising upper and lower pairs of cooperating working rolls and backing rolls therefor which constitute the sole means engaging said rolls between their ends for preventing them from being deflected by the rolling stresses encountered, the diameter of said backing rolls and that of said working rolls having a ratio of approximately 4:1.
33. Apparatus for reversely bending sheet metal comprising upper and lower pairs of cooperating working rolls and backing rolls therefor which constitute the sole means engaging said rolls between their ends for preventing them from being deflected by the rolling stresses encountered, the diameter of said backing rolls and that of said working rolls having a ratio of not less than 3:1.
34. Roller leveler apparatus comprising a series of working rolls for producing relatively sharp bends for effectively leveling sheet metal, and a series of working rolls for producing relatively light bends for straightening curved end portions of said sheet metal.
35. Roller leveler apparatus comprising a series of relatively small working rolls for producing relatively sharp bends for effectively leveling sheet metal, and a series of relatively large working rolls for producing relatively light bends for straightening curved end portions of said sheet metal.
36. In a metal working machine, a plurality of groups of four relatively small working rolls mounted in pairs one above the other, and a backing roll for each of said pairs of working rolls which comprises the sole means for preventing deflection of the working rolls, said backing roll being sufficiently larger than the working rolls and the working rolls mounted sufficiently close together against it to prevent objectionable deflection of the working rolls by the rolling forces encountered.
37. In a metal working machine the combination of a pair of relatively small working rolls, a relatively large backing roll therefor comprising a rolling unit and said backing roll comprising the sole means for preventing flexing of both of said working rolls in any direction when subjected to rolling stresses, the working rolls being mounted sufficiently close together to permit the backing rolls to function in the manner set forth.
38. The method of removing scale from, leveling and straightening metal strip consisting in passing it continuously through a series of wave-shaped roll passes in which it is reversely deflected at a relatively sharp angle, tensioning it while it is being so worked and then passing it without appreciable tension through a final wave-shaped roll pass in which the deflection effected is of a diminishing character as compared to that of the first-mentioned passes.
39. The method of removing scale from, leveling and straightening metal strip consisting in passing it continuously through a series of wave-shaped roll passes in which it is reversely deflected at a relatively sharp angle but to a diminishing extent in each succeeding pass, subjecting it to tension between said passes and then passing it without appreciable tension through a final pass of the same general character in which it is subjected to a deflection of a lesser degree of curvature.
40. The method of removing scale from, leveling and straightening strip metal consisting of progressively bending it reversely at spaced intervals in a wave-like manner about rolls having a relatively small radius of curvature in each

direction, tensioning it while so bending it and finally, reversely bending it progressively about a somewhat larger radius of curvature in each direction without appreciable tension.

5 41. The method of treating metal strip which comprises passing it through a series of wave-shaped roll passes in certain of which it is bent reversely about rolls having a relatively small radius of curvature and then finally through a

pass in which it is reversely bent about rolls having a somewhat large radius of curvature.

42. The method of treating metal strip which consists in continuously passing it through a series of relatively small rolls arranged in staggered relation to loosen the scale, remove bulges, kinks, etc., and then passing it through a similar arrangement of larger rolls to flatten it.

FLORENCE C. BIGGERT, JR.

CERTIFICATE OF CORRECTION.

Patent No. 2,004,596.

June 11, 1935.

FLORENCE C. BIGGERT, JR.

It is hereby certified that error appears in the printed specification of the above numbered patent requiring correction as follows: Page 7, second column, line 74, claim 40, strike out the words "rolls having"; and that the said Letters Patent should be read with this correction therein that the same may conform to the record of the case in the Patent Office.

Signed and sealed this 16th day of July, A. D. 1935.

(Seal)

Leslie Frazer
Acting Commissioner of Patents.
